UNITED STATES PATENT OFFICE.

STEPHEN D. BAKER, OF NEW YORK, N. Y.

DESIGN FOR A RAZOR CABINET.

Application filed August 26, 1927. Serial No. 23,210. Term of patent 14 years.

hom it may concern:
own that I, STEPHEN D. BAKER, a f the United States of America, in New York, in the county and New York, have invented a new,
and ornamental Design for a Razor
of which the following is a specifica-rence being had to the accompanying, forming part thereof.

The figure is a perspective view of a razor
cabinet showing my new design.

I claim:

The ornamental design for a razor cabinet,
as shown.

STEPHEN D. BAKER.
